United States Patent Office

Des. 180,330
Patented May 21, 1957

180,330

PERSONNEL CAGE FOR AERIAL APPARATUS

James Howard Holan, Rocky River, Ohio, assignor to
J. H. Holan Corporation, Cleveland, Ohio, a corpora-
tion of Ohio

Application February 6, 1956, Serial No. 40,053

Term of patent 14 years

(Cl. D14—3)

Fig. - 1

Fig. - 3

Fig. - 2

Fig. - 4

Fig. 1 is a perspective view of a personnel cage for aerial apparatus embodying the present invention;

Fig. 2 is a perspective view taken from the diagonally opposite corner from that of Fig. 1;

Fig. 3 is a bottom plan view; and

Fig. 4 is a side elevation view, those portions shown in broken lines being for purposes of illustration only.

I claim:

The ornamental design for a personnel cage for aerial apparatus, as shown and described.
